[57] CLAIM

The ornamental design for a walking pad, as shown and described.

DESCRIPTION

FIG. 1 is a front elevational view of the walking pad showing my new design;

FIG. 2 is a rear elevational view thereof;

FIG. 3 is a left side elevational view thereof;

FIG. 4 is a right elevational view thereof;

FIG. 5 is a top plan view thereof;

FIG. 6 is a bottom plan view thereof; and,

FIG. 7 is a perspective view of the walking pad attached to an ankle/foot orthosis showing my new design.

No part of the phantom lines in FIG. 7 form any part of the invention.
